GRAHAM TRIPPE, OF DETROIT, MICHIGAN.

HEADLIGHT.

1,413,811.

Specification of Letters Patent. Patented Apr. 25, 1922.

Application filed October 20, 1920. Serial No. 418,172.

To all whom it may concern:

Be it known that I, GRAHAM TRIPPE, a citizen of the United States, residing at Detroit, in the county of Wayne and State of Michigan, have invented certain new and useful Improvements in Headlights, of which the following is a specification.

The present invention relates to headlights such as are used on motor vehicles and consists in an attachment of novel construction, which is readily applicable to existing forms of such headlights. Such attachment includes a supplementary reflector shaped to lie in front of and cover the lower half of the regular reflector of the headlight, and having for its object to focus a portion of the light so as to provide a depressed beam for distant illumination, and to diffuse other portions of the reflected light so as to illuminate the roadway between such beam and the vehicle. The result aimed at is the proper illumination of the roadway, both near and far, without glare or concentration of light in the line of vision of occupants of an approaching vehicle, as is the case when the ordinary reflector is used alone, to secure such effects by properly directing the light rather than by diminishing the degree of illumination afforded by the headlight.

This supplementary reflector comprises a plate affording two differently shaped reflecting surfaces merging into each other, one being parabolic and the other conical, the effect of which is to direct the light rays, which strike the supplementary parabolic reflector, in a downwardly inclined beam and to diffuse those which strike the conical surface in diverging directions with respect to the axis of the headlight. The arrangement of the device is such that the lamp filament is located in front of the focus of the regular parabolic reflector of the headlight, while it lies behind the focus of the parabolic portion of the supplementary reflector and therefore behind the conical portion thereof. In other words, the two parabolic reflecting surfaces are offset from one another and the lamp filament is located between the foci of the same, the effect being that the rays from both said surfaces are directed slightly downwardly from the axis of the lamp. The rays reflected from the surfaces of each of the parabolic reflectors are directed, of course, parallel to each other, and the bundles of rays from the two parabolic reflecting surfaces merge into a beam directed

to be effective below the horizontal axis. The rays reflected from the conical portion of the supplementary reflector are directed at varying and divergent angles, whereby a diffused and non-glare illumination is available for the roadway and objects in the vicinity of the vehicle. Therefore, all the concentrated reflected rays will be directed into the area below the axis of the headlight, and will be most effective on the roadway at a point considerable in advance of the vehicle, while the area below and to the sides of the path of the concentrated rays will be lighted by a non-glaring diffused light.

One of the features of my invention is the ready adaptability of the supplementary reflector to the ordinary or existing types of parabolic headlights in use, without the necessity of modifying the structure of the latter in any way. Other objects and advantages of the invention will appear from the following detailed description in which reference is made to the accompanying drawing. The embodiment of the invention shown and the representation of the ordinary headlight to which the invention is applied, are by way of example only, and are not to be considered as limiting the invention or its application to the exact forms shown.

In the drawing referred to—

Fig. 1 is a side elevation of an automobile headlight equipped with my reflector attachment, shown in dotted lines;

Fig. 2 is a central longitudinal section of the same;

Fig. 3 is a front view of the same;

Fig. 4 is a front view of the supplementary reflector and its attaching means;

Fig. 5 is a side view of the same, and

Fig. 6 is a diagrammatic view illustrating the arrangement of the lamp filament in relation to the foci of the offset parabolic reflectors.

In these views I have illustrated my attachment as applied to a conventional type of automobile headlight comprising the U-shaped supporting bracket 1, the casing 2, detachable rim 3, lamp support 4, the lamp 5, front glass 6, and parabolic reflector 7. The focusing socket 11 is axially adjustable by the usual focusing screw 8, so that the lamp filament can be properly located with respect to the foci of the reflectors, as hereinafter fully set forth. The supplementary reflector 8 covers the lower half only of the

reflector 7; its upper edge 9 lies in the plane of the horizontal axis of the headlight and is provided with a semi-circular recess 10 adapted to fit loosely around the lower half 5 of the focusing socket 11. It is held in place thereon by a spring clip or collar 12, which is clamped on to said socket by a screw 13, passing through the ears of the clip, or the collar may be held in place on 10 the socket 11 by a set screw or the like. This collar or clip in instances may be provided with oppositely-disposed lateral seats 14, in which engage pivot projections 15, formed on the reflector 8 at the ends of the recess 15. In this way the reflector can swing in the longitudinal plane of the headlight sufficiently to adapt itself to slight variations in the shape of the fixed reflectors of different types of headlights. Normally, 20 however, the spring clip 12 may be made integral with the reflector, in which case, of course, the latter is not flexibly supported and the two are held in fixed relationship.

As stated above, the supplementary reflector, which constitutes my invention, comprises two distinct reflecting surfaces or portions, a smaller central parabolic portion 16 and a larger outer conical portion 17, the two surfaces merging into each other at the 30 line 18.

I have mentioned that the filament of the lamp 5 is located slightly in advance of the focus of the parabolic reflector 7, whereby rays of light from the lamp striking the 35 upper part of said reflector are directed forwardly at a slightly depressed angle, as indicated by the lines A in Fig. 2, and that said filament lies slightly behind the focus of the parabolic portion 16 of the supplementary reflector 8, so that the rays reflected from it are also directed downwardly as indicated by the lines B in said figure. This is graphically shown in Fig. 6 wherein the filament of the lamp is designated F; the 45 focus of the parabolic reflector 7 is designated f, and the focus of the parabolic portion 16 of the supplementary reflector 8 is designated f'.

The rays striking the conical portion 17 50 of the supplementary reflector are likewise directed somewhat downwardly, as indicated by the lines C and D in Fig. 2 and, at the same time, are diffused or diverted laterally as well as vertically, that is to say 55 the rays reflected from said conical portion are not directed parallel to each other but at angles constantly varying from the inner edge to the outer edge of said conical surface so that the light reflected therefrom is 60 diffused and of a non-glaring character.

The only rays which are directed horizontally forward are those from the lamp itself, there being no horizontal reflected rays. The parallel rays reflected from the 65 parabolic surfaces 7 and 16 are directed

downwardly as shown and described and the rays reflected from the conical surface 17 are divergent and spread fan shaped, so to speak, so that a headlight equipped with my attachment sends forth no blinding glare 70 to annoy and confuse pedestrians or other motorists.

The attachment or supplementary reflector can easily and quickly be applied to existing headlights by simply removing the 75 rim 3 and glass 6, taking out the bulb 5 and clamping the ring 12 on to the lamp socket; it can, of course, be as quickly and easily removed.

It must be understood that the location of 80 the lamp filament relatively to the foci of the parabolic reflectors has a very important bearing upon the proper functioning of the headlight. The extent of the collar 12 to the rear of the reflector 8 85 establishes the minimum axial distance by which the reflectors 7 and 8 will be offset, which distance will establish the distance between the respective foci. The collar 12 constitutes a guide for determining the 90 proper adjustment of the focusing socket 11, said collar being of such width that when the forward end of the socket 11 is flush with its front edge, the filament of a predetermined form of lamp will of necessity be in front of the focal point of the 95 reflector 7. This will assure the proper depression of the rays from the reflector 7. The extent of the collar forwardly from the reflector 8 determines in the same 100 manner the position of the lamp filament relative to the focus of that reflector, so that the proper relationship of the two is established by the mounting of the reflector 7 upon the focusing socket. Once the 105 device is secured in place, no adjustment of the focusing socket can be effective to raise the concentrated beam above the horizontal axis, movement of the lamp filament back of the focus of the upper reflector being prevented by abutment of the collar against said reflector, while the relationship of the lamp filament to the focus of 110 the lower parabolic reflector as well as to the conical reflector 17, is fixed. By provision of a collar of the proper width, moreover, a definite guide is provided for accomplishing location of the filament F of a given lamp 5 between the foci of the 115 reflectors 7 and 16 at a point where the resultant reflections will coincide in a beam of maximum intensity. Experience has shown what these distances should be and the collars are made accordingly. In applying my attachment to an ordinary headlight, 120 the adjustable socket has to be moved forwardly sufficient to give space enough to mount the collar 12 thereon, in the intended manner which, when the collar 125 is of the proper width, brings the filament 130

in front of the focus of the regular reflector, and in rear of the focus of the parabolic portion 16 of the supplementary reflector. This insures proper focusing of 5 the lamp in an installation for which the reflector is designed, and unless the lamp is so focused the attachment cannot be properly applied. Therefore, before installation can be effected the necessary 10 adjustment of the parts must be made which automatically will establish proper focusing of the lamp, without the necessity of having to make an actual test of the adjustments or subsequent corrective adjustments. 15

Having thus described my invention what I claim is:

1. The combination with a headlight having a reflector and an axially disposed lamp 20 mounting, of a supplementary reflector shaped to overlie substantially the lower half of the primary reflector, said supplementary reflector having the portion of its reflecting surface adjacent its axis of parabolic contour and the balance of its reflecting surface of conic contour, and means 25 for supporting said supplementary reflector upon the lamp mounting in such fashion that the focus of its parabolic portion is 30 in front of the focus of the primary reflector exposed to the light from the lamp.

2. The combination with a headlight having a parabolic reflector and an adjustable mounting for supporting a luminant, of a 35 supplementary reflector adapted for insertion within the headlight and shaped to

cover substantially the lower half of the headlight reflector, said supplementary reflector having its reflecting surface shaped to reflect rays from the luminant in directions inclined downwardly from the axis of the headlight reflector, and attaching means whereby the supplementary reflector may be fixedly mounted on the adjustable mounting, said attaching means being 40 adapted to cooperate with the headlight reflector as a stop member effective to prevent retraction of the adjustable mounting to a position where the luminant may occupy a position at or behind the focal point 45 of the headlight reflector.

3. The combination with a headlight having a reflector and an adjustable lamp support, of a supplementary reflector insertable into the headlight to occupy a position in 50 covering relationship to the lower portion of the headlight reflector, and means for mounting said supplementary reflector upon the lamp support, said means being arranged for cooperation with the headlight 55 to limit rearward movement of the lamp therein, said means cooperating with the lamp support to prevent forward movement of the lamp relative to said supplementary reflector.

In testimony whereof I have hereunto subscribed my name in the presence of two subscribing witnesses.

GRAHAM TRIPPE.
